UNITED STATES PATENT OFFICE

HENRY ALBERT MITCHELL, OF WOOLER, ONTARIO, CANADA

ELECTRIC FUEL WARMER FOR INTERNAL COMBUSTION ENGINES

Application filed April 28, 1930. Serial No. 447,616.

This present invention relates to new and useful improvements in an electric fuel warmer for internal combustion engines.

The primary object of the invention resides in the provision of an electric fuel warmer for internal combustion engines which will facilitate quick starting of operation of the engine in low temperatures.

Another object of the invention resides in the provision of an electric fuel warmer for internal combustion engines which will make it possible to readily start the internal combustion engine in the coldest weather.

A further object of the invention resides in the provision of an electric fuel warmer for internal combustion engines by means of which a small auxiliary supply of fuel may be readily heated before being fed to the intake manifold to assure quick combustion of the fuel for instant starting of the engine.

The invention has for a still further object the provision of an electric fuel warmer for internal combustion engines which is of extremely simple and inexpensive construction and operation and may be readily controlled by the operator from the instrument board.

The invention has for a still further object the provision of an electric fuel warmer for internal combustion engines which is of such simple type and arrangement that it may be readily incorporated in motor vehicles and the like without material alterations in the same either when building the motor vehicles, trucks, etc., or after completion of the same.

To the accomplishment of these and related objects as shall become apparent as the description proceeds, my invention resides in the construction, combination and arrangement of parts as shall be hereinafter more fully described, illustrated in the accompanying drawing, and pointed out in the claims hereunto appended.

The invention will be best understood and

can be more clearly described when reference is had to the drawing forming a part of this disclosure, wherein like characters indicate like parts throughout the several views.

In the drawing:

Figure 1 is a vertical longitudinal section through the complete structure, showing the application of the same to the conventional motor vehicles now in general use;

Figure 2 is a transverse section on an enlarged scale, taken substantially on the plane of line 2—2 of Figure 1, looking in the direction indicated by the arrows;

Figure 3 is a transverse, vertical section through the auxiliary fuel supply tank, showing a slightly modified form of the invention;

Figure 4 is a view similar to Figure 3 showing a further modified form of the invention; and

Figure 5 is an elevation of the form of the invention shown in Figure 4.

Referring more in detail to the drawing, it will be noted that the auxiliary fuel supply tank 6 is designed for convenient location between the instrument board 7 and the intake manifold 8 of the motor vehicle engine. A cover 9 is provided for the tank 6 and a small discharge tube 10 depends from the bottom of the tank 6 with its lower end threaded in the upstanding branch 11 of a substantially T-shaped pipe connection 12, from one end of which extends the fuel feed tube 13 leading to the engine intake manifold 8, the opposite ends of said tube 13 being threaded in the pipe connection 12 and the side of the intake manifold 8, respectively. A needle valve 14 is adjustably threaded in the other end of the pipe connection 12 with its point 15 working against and adjustable in respect to the valve seat 16 in the pipe connection 12. A small reservoir or pocket 17 is provided in the centre of the pipe connection 12 and appropriate packing 18 and a cap 19 are pro-

vided on the end of the pipe connection 12 through which the needle valve 14 operates. A universal joint connection 20 is provided between the outer end of the stem or shank 5 of the needle valve 14 and the needle valve adjusting rod 21 which is rotatably mounted through the instrument board 7 and provided with a knurled nut 22 or the like on its free extremity to provide for easy turning of 10 the adjusting rod 21 by the operator. A switch 23 is also provided on the instrument board 7 for closing a circuit through the current conducting wires 24, one of which is connected with the storage battery 25 of the 15 motor vehicle or any other appropriate source of electrical energy. The other wire 24 and a wire 26 leading from the source of electrical energy 25 connect with the pair of binding posts 27 extended through and insulated from the wall of the auxiliary fuel supply tank 6 and having connected on their inner ends the terminals of the electrical heating coil 28 resting in and coiled around the bottom of the tank 6. An insulating disk 29 is positioned in the bottom of the tank 6 and provided with an upturned annular flange 30 engaging the inner wall of the tank 6; while a central opening 31 is also provided in the insulating disc 29 registering with and 20 of greater diameter than the bore of the small discharge tube 10 of said tank 6. It is therefore evident that the electrical heating coil 28 is thoroughly insulated from the tank 6 by the disk 29 without the latter interfering 25 in any manner with free discharge of the fuel from the tank 6.

In the modified form of the invention disclosed in Figure 3, the electrical heating coil 28a is suspended in an insulating support 32 depending in the auxiliary tank 6a, from the tank cover 9a, which also carries the binding posts 27a, to which are attached the terminals of the said electrical heating coil 28a, and from which binding posts 27a extend the current conducting wires 26a and 24a.

In the modified form disclosed in Figures 4 and 5, the electrical heating coil 28b is completely submerged in the liquid fuel in the supply tank 6 and suspended by its opposite 50 ends on the depending ends of the binding posts 27b extended through the cover 9b for the body of the tank 6b. The body of the tank 6 is in the form of a cylinder constructed from glass or other appropriate material 55 and has its upper edge engaged in an annular groove 33 provided in the under face of the cover 9b while the lower edge of the body of the tank 6b rests in a similar annular groove 34 provided in the upper face of the solid bottom 35 for the tank body. The electric heating coil 28b occupies a position in the body of the tank 6b just above the solid bottom 35 for the tank body and the latter has a transverse enlargement 36 on its under face 60 with a threaded extended end 37 for connec-

tion with the fuel feed tube 13 leading to the engine intake manifold 8, similar to the other forms of the invention disclosed in this application. A central discharge opening 38 is provided in the solid bottom 35 connecting 70 with the longitudinal passage 39 of smaller diameter extending from the opening 38 through the threaded extended end 37 of the enlargement 36. A needle valve 40 is threaded in the other end of the enlargement 36 with its point 41 adjustable with respect to the valve seat 42 provided therefor in the inner end of the passage 39, at its connection with the opening 38. A pair of spring clamp members 42a are mounted at their lower ends on gears 43 extended radially from the edge of the solid bottom 35 for the body of the tank 6b and provided with angularly bent free ends 44 which are adapted to be swung over the edge of the cover 9b to firmly clamp the cover 9b on the cylindrical body of the tank 6b and retain both the cover 9b and the body of the tank 6b firmly on the solid bottom 35 for the tank body. These spring clamp members 42a may be readily engaged over the cover 9b or withdrawn therefrom, as desired. It is also to be noted that the spring clamp members 42a are of substantially elongated link form so as to provide for a firm holding of the cover 9b by said spring clamp members 42a.

As the construction of the device has thus been described in detail, brief reference is now had to its use and modus operandi: When use of the fuel from the tank 6, 6a or 6b is not required, the switch 23 is left open while the needle valve 14 is closed firmly against the valve seat 16. Should there be any difficulty in starting the operation of the engine, due to a low atmosphere of temperature or a cold engine, it is simply necessary to close the switch 23 and open the needle valve 14 by means of the knob 22 on the rod 21. This will result in quick heating of the small amount of fuel in the tank 6 by the electrical heating coil 28, 28a or 28b and a free flowing of the fuel through the tube 10, pass the needle valve 14 and a by way of the tube 13, to the engine intake manifold 8. This heated fuel may be readily ignited within the engine cylinder to effect quick starting thereof. When the engine has been started in this manner, the operation may be continued in the usual manner from the regular fuel supply and the needle valve 14 closed and the switch 23 again opened to break the circuit through the electrical heating coil 28, 28a or 28b.

From the foregoing description taken in connection with the accompanying drawing, it will be manifest that an electric fuel warmer for internal combustion engines is provided that will fulfill all the necessary requirements of such a device but as many changes could be made in the above description and

many apparently widely different embodiments of my invention may be constructed within the scope of the appended claims without departing from the spirit or scope thereof, it is intended that all matters contained in the said accompanying specification and drawing shall be interpreted as illustrative and not in a limited sense.

Having thus described my invention, what I claim as new and desire to secure by Letters Patent is:—

1. An electric fuel warmer for internal combustion engines including an auxiliary fuel tank with the top and bottom thereof formed separate from the body of said tank; means carried by the bottom for removable engagement over the top of the tank to firmly clamp together said bottom, top and body of the tank and form liquid tight connections therebetween; binding posts depending through said cover of the tank; an electric heating coil extended between the depending ends of said binding posts and completely submerged in the liquid content of the body of said tank adjacent the bottom thereof; said bottom of the tank being solid and having a transverse extension on its under face with a threaded end projecting for connection with the fuel feed pipe leading to the intake manifold of the engine; a needle valve adjustable in said transverse extension of the body bottom and normally closed against the valve seat in the longitudinal fuel passage through said extension; a source of electrical energy; electrical connections between said source of electrical energy and a binding post to complete a circuit through the same and through said electric heating coil; and a control switch for said circuit adjacent to the controlling means for said needle valve.

2. An electric fuel warmer for internal combustion engines including an auxiliary fuel tank; an insulating disc within said auxiliary fuel tank and resting on the bottom thereof; said insulating disc having a central opening registering with the bore of the discharge tube of said auxiliary fuel tank; said insulating disc having an annular upstanding flange engaging the inner wall of said auxiliary fuel tank; a heating coil resting on said insulating disc; terminal binding posts connected with the ends of said coil and extended through the flange of said insulating disc and through the wall of said tank; current conducting wires connecting with said binding posts and with a source of electrical energy; and a control switch in the path of one of said current conducting wires to control the current through said electric heating coil.

3. An electric fuel warmer for internal combustion engines including an auxiliary fuel tank; a removable cover for said auxiliary fuel tank; binding posts carried by said

cover; an electric heating coil suspended from said binding posts into said auxiliary fuel tank; an insulated support for said electric heating coil suspended from said cover; current conducting wires connected to said binding posts for supplying electric current to said electric heating coil and completing a circuit therethrough; and a control switch for said circuit.

In testimony whereof I hereunto affix my signature.

HENRY ALBERT MITCHELL. [L. S.]
